DES. 2241

Lewis Rathbone, of Albany, New York.
Letters Patent No. 2241 Dated Jan'y 16-1866.
Design for the Plates of a Stove.

The schedule referred to in these Letters Patent and making part of the same.

Is it known that I, Lewis Rathbone, of the City of Albany, State of New York, have produced a new ornamental design for the Plates of a Wall Stove, and I hereby declare the annexed drawings exhibiting in perspective a stove with the plates in place, to be a full and accurate delineation of the said plates with their ornaments. The said stove being known as the Monitor.

What I claim as my production and desire to secure by Letters Patent is the design for a stove as shown and described.
